DESIGN FOR A DOMESTIC ICE CREAM FREEZER

Harry J. Kettleborough, Mendota, Ill.

Application February 3, 1938, Serial No. 74,823

Term of patent 14 years

To all whom it may concern:

Be it known that I, Harry J. Kettleborough, a citizen of the United States and a resident of Mendota, in the county of LaSalle and State of Illinois, have invented a new, original, and ornamental Design for a Domestic Ice Cream Freezer, of which the following is a specification, reference being had to the accompanying drawing, forming a part thereof.

The drawing is a perspective view of a domestic ice cream freezer showing my design, the sides not shown being identical with those shown, except for the crank handle shown at the right of the figure.

I claim:

The ornamental design for a domestic ice cream freezer, as shown and described.

HARRY J. KETTLEBOROUGH.
